UNITED STATES PATENT OFFICE.

JOSEPH BAVETT, OF BALTIMORE, MARYLAND.

DOOR CLOSER.

Application filed November 3, 1923. Serial No. 672,490.

This invention relates to devices for automatically closing doors and although capable of use in connection with any swinging door, it is particularly adapted for use 5 in closing the doors of vehicles such as taxi-cabs or other closed body automobiles.

One object of my invention is to so construct and mount the parts that they may be readily attached without change in the 10 construction of the vehicle door or body wall, and when attached are inconspicuous and offer no obstruction to free use of the door way.

A further object is to provide a simple 15 and inexpensive construction having the minimum number of parts so connected that they cannot get out of order or fail to properly operate.

In the accompanying drawings:

20 Fig. 1 is an elevation of the inner side of a portion of a vehicle wall and door having my improved device attached thereto.

Fig. 2 is a section on the line 2—2 of 25 Fig. 1, but on a larger scale, and

Fig. 3 is a perspective view of a rod forming a part of the construction.

I have illustrated my improved construction as attached to a vehicle body wall 10 30 having a hinged door 11. It will of course be evident that the drawings include only a conventional illustration of such wall and door, as the details thereof form no portion of my invention.

35 My improved device includes two relatively movable and yieldingly connected parts, one adapted to be attached to the door and the other to the door casing upon opposite sides of the hinge center, and upon 40 the surface of the wall and door opposite to that having said hinge center. One of these members is in the form of a tube 12 and the other in the form of a rod 13. Although in some constructions the tube may

45 be secured to either the casing or the door, in vehicles it is preferable that the tubular member 12 be secured to the casing or vehicle body wall instead of to the door. As shown, it is secured to the inner surface of 50 the wall 10 adjacent to the plane of the upper edge of the door 11 and on the side of said wall opposite to the pintle of the hinge 14. The tubular member extends in a direction substantially at right angles to 55 the edge of the door opening and is rigidly secured in any suitable manner as for

instance by lugs 15 and attaching screws. The member 13 is pivotally connected to the door 11 by means of a bracket 16 which has a pair of spaced lugs or ears receiving 60 an eye 17 on the end of the member 13 and a suitable pivot pin. The tubular member 12 has a slot 18 extending lengthwise thereof at the end portion nearest to the door edge, and of a width slightly greater 65 than the diameter of the rod 13. The rod 13 has a head 19 which is of greater vertical dimension than the slot so that it is guided lengthwise of the tubular member and cannot escape from the slot when the 70 parts are secured in position for use. The parts are so positioned that when the door is closed the head 19 is adjacent to the end of the slot farthest from the door edge. Within the tubular member is a coil spring 75 20 which acts on the head 19 and exerts a pressure tending to move the head 19 away from the edge of the door opening and thus pull the door to closed position. Although in some constructions I may employ a compression spring on the side of the head toward the door opening, I preferably employ a tension spring on the side of the head away from the door opening. This permits the spacing of the end of the tubular 80 member as close to the door opening as desired. There is also provided means whereby the tension of the spring may be varied to exert a greater or lesser pull on the rod 13. This tension adjusting means 85 is shown as a screw 21 extending through the end of the tubular member 12 and having threaded engagement with a nut 22 connected to the end of the spring. By rotating the screw the nut may be moved toward or away from the end of the tubular member and the spring put under greater or less tension.

90 It will be noted that in attaching the device it is merely necessary to insert the proper screws to hold the lugs 15 and bracket 16 in place, and that the device when installed comes above the heads of the passengers in the vehicle and close to the roof so as to be inconspicuous. The device includes 95 the minimum number of parts, and none of these is expensive to manufacture or assemble. The head 19 may be inserted through the slot when the rod is turned so as to bring the head lengthwise of the slot and the spring 100 110 may be connected to the head in any suitable manner, as for instance by passing the end of

the wire through a hole in the rod, or by bending it around the head. The rod 13 may be so curved in respect to the height of the bracket 16 and the positioning of the parts that it will clear the edge of the door and of the door casing when the door is opened through 90°. It may then bind on the edge of the door opening as shown in Fig. 2, so as to act as a door stop and prevent the door from being opened to any further extent. The spring exerts a continuous pull on the rod 13 so that after the door has been opened the device will automatically close the door when the passenger or attendant lets go of the door.

The device serves not only as a door closer, but it acts to hold the door in closed position and prevent it from flying open if the latch is not properly engaged when the vehicle starts in motion.

Having thus described my invention, what I claim as new and desire to secure by Letters Patent is:

A door closer for automobiles and adapted

to exert yielding tension tending to hold the door in closed position, said door closer including a tubular member having lugs integral with the wall thereof at opposite ends for securing said tubular member to the inner surface of the wall of the automobile with one end adjacent to the door opening, the outer side of said tubular member at said last mentioned end portion having a longitudinally extending slot, a bracket adapted to be secured to the inner surface of the door adjacent to the hinged edge, a pull rod pivotally connected to said bracket, and having a head portion within said tubular member and connected to said rod through said slot, a tension spring within said tubular member and connected to said head portion, and tension adjusting means for connecting the other end of said spring to the end of the tubular member farthest from said door opening.

Signed at Baltimore in the State of Maryland this 30th day of October, A. D. 1923.

JOSEPH BAVETT.
